COMBINED MAGNETIC TAPE STEREO PLAYBACK DEVICE AND SPEAKER CABINET UNIT OR SIMILAR ARTICLE

David Krechman, 329 S. McCarty Drive,
Beverly Hills, Calif. 90212

Filed Oct. 23, 1965, Ser. No. 87,859

Term of patent 3½ years

(Cl. D26—14)

FIG. 1.

FIG. 2.

FIG. 3.

FIG. 4.

FIG. 1 is a front, top and right side perspective view of a combined magnetic tape stereo playback device and speaker cabinet unit or similar article, showing my new design;

FIG. 2 is a left end elevational view, the right end being substantially a mirror image thereof;

FIG. 3 is a rear elevational view; and

FIG. 4 is a bottom plan view thereof.

I claim:

The ornamental design for a combined magnetic tape stereo playback device and speaker cabinet unit or similar article, as shown and described.
